CHARLES PETERSON, OF DUBLIN, IRELAND.

TOILET OR HAIR COMB.

1,094,013.

Specification of Letters Patent. Patented Apr. 21, 1914.

Application filed March 21, 1910. Serial No. 550,771.

To all whom it may concern:

Be it known that I, CHARLES PETERSON, a subject of the King of Great Britain, residing at Dublin, Ireland, have invented 5 new and useful Improvements in Toilet or Hair Combs, of which the following is a specification.

This invention has reference to an improved toilet or hair comb which is designed more particularly for use by persons 10 possessed of a large quantity of hair.

It is well known that very frequently hair is broken off or torn out when being combed by reason of the fact that the hair is 15 jammed fairly tightly between the teeth of the comb and particularly is this the case if the teeth of the comb be thicker at their base than at their free ends. It is possible of course to in a way reduce this jamming 20 or wedging of the hair between the teeth by making combs having their teeth spaced farther apart but although this method of overcoming the difficulty is very simple it is not really practicable inasmuch as the 25 process of combing has to be prolonged for an inordinately lengthened period if the proper straightening out or combing of the hair is to be effected. That is to say the greater the number of teeth for a given 30 length of comb the more thoroughly will the combing be effected. Further the points of the teeth should be in alinement to enable the proper dividing or parting of the hair to be readily effected.

35 It has been proposed to remedy the defect indicated by making a comb with two convergent series of teeth, carried by a common back, which teeth alternate with each other and the points of which interdigitate and occupy a single line, but such a comb exerts only a slight combing action upon the hair owing to the fact that the shanks 40 of the teeth diverge from the points and allow the hair to pass too freely between them.

45 My invention consists broadly in a comb in which the end portions or point ends of all the teeth are in alinement for a substantial portion of the length of the teeth and 50 in which the other or shank portions of the said teeth diverge alternately to one side and the other. With a comb so constructed, jamming or wedging of the hair between the teeth is entirely obviated while at the

same time the combing action is at least 55 equivalent to that of an ordinary comb of the same length with an equal number of teeth of a length corresponding to that of the aforesaid alined portions of the teeth of my improved comb. 60

My improved comb may be made from a single blank bent on itself to form the desired construction, or it may be made of two separate parts connected together and each having a row of teeth spaced a double 65 distance apart.

Figure 1 is a plan view of a portion of a blank from which the comb is formed, in accordance with my invention; Fig. 2 is an end elevation of the complete comb; Fig. 70 3 is a detail of the comb in side elevation showing the lateral arrangement of the two series of teeth; Fig. 4 is a horizontal sectional detail on the line A—B, Fig. 2, taken through the shank portion of the teeth; Fig. 75 5 is a similar section, taken through the point portion of the point, on the line C—D, Fig. 2; Fig. 6 is a view similar to Fig. 1, but showing tapered teeth; Fig. 7 is a detail in side elevation of the comb made from 80 the blank illustrated in Fig. 6. Fig. 8 is an end view of a comb of a different style from that shown in Fig. 2 but embodying my invention; Fig. 9 is a similar view of another style of comb embodying my invention; Fig. 85 10 is an end view of still a different style of comb embodying my invention.

Fig. 1 of said drawings shows a portion of a flat strip of material—such as vulcanite—from each longitudinal edge or side of which parts *a* are cut out so as to leave teeth *b*, *b*¹ 90 projecting from a central part *c* and which teeth by pressing, cutting or any other suitable process may be shaped so as to have the desired sectional shape. The teeth on each side of the central part *c* are spaced apart twice (more or less) the distance that the teeth are to be in the finished comb and one set of teeth (*b*) is to be opposite the spaces between the other set of teeth (*b*¹). I next 100 bend the central part *c* transversely of its length until it has the form shown in edge or end view in Fig. 2 that is to say until the point ends of both sets of teeth *b*, *b*¹ are in alinement, the said teeth being also equidistant from each other as shown in side elevation in Fig. 3. As will be understood 105 from a consideration of Figs. 2 and 3 al-

though the point ends of the teeth are close together their shanks are farther apart as the shanks of each set of teeth are, so to speak, removed from between the shanks of 5 the other set. In order to show how much the spaces between the teeth at the shank ends are—in the example illustrated—greater than the spaces between the point ends of the teeth I have shown in Fig. 4 the position of 10 the shanks of the teeth at the section on line A—B of Fig. 2 and in Fig. 5 the position of the point ends of the teeth at the section on line C—D also of Fig. 2. The teeth shown in Figs. 1, 2 and 3 are shown of equal thickness throughout their length. Figs. 6 and 15 7 show similar views to Figs. 1 and 2 but the teeth in Figs. 6 and 7 are made of a tapering shape.

In Figs. 8 and 9 I have shown end views 20 of other shapes of combs made in accordance with my invention, and the combs shown in these figures differ from each other merely in the shape which the shanks assume at or near the back.

25 In Fig. 10 I have illustrated still another embodiment of my invention wherein the comb is made of two separate parts each having a row of teeth spaced a double distance apart, said parts being connected by 30 rivets *r*.

What I claim as my invention and desire to secure by Letters Patent is:—

In a toilet or hair comb, a back and teeth extending therefrom, said teeth having straight bodies of considerable length which 35 are parallel to each other and in alinement in the direction of the length of the comb whereby all teeth act alike on the hair, the straight bodies of the teeth being connected to the back by shank portions which extend 40 outwardly from the bodies of the teeth and then inwardly toward the back, the shanks of alternate teeth being situated on one side of the central line of the comb and the shanks of the remaining teeth being situated on the 45 other side whereby spaces of double width are presented between adjacent shanks on each side of the comb and the shanks of adjacent teeth are widely separated so that the hair which has been raised by the points of 50 the comb teeth and carried into the wide spaces will pass between the shanks in comparatively straight lines.

In testimony whereof I have signed my name to this specification in the presence of 55 two subscribing witnesses.

CHARLES PETERSON.
